MIXING DEVICE

William A. McLean, Geneva, N. Y., assignor to
Geneva Processes, Inc., Geneva, N. Y., a corpora-
tion of New York

Original application January 5, 1938, Serial No.
183,549. Divided and this application June 2,
1941, Serial No. 396,337

4 Claims. (Cl. 259—8)

This invention relates to mixing and emulsifying devices, and more especially to devices for mixing emulsions which may or may not be colloidal, such as mayonnaise, salad dressings, and insecticides.

This application is a division of my co-pending application Serial No. 183,549, filed January 5, 1938.

One of the objects of this invention is to provide a mixing device which is capable of quickly producing a colloid or a mixture of the desired homogeneity.

Still another object of this invention is to provide a mixing device which is simple in construction and may be readily adjusted to produce a product having the desired characteristics.

Yet another object of this invention is to provide a mixing device provided with a rotor and provided with means by which the material which is to be mixed can be fed in a relatively small stream upon the center portion of the rotor.

A further object of this invention is to provide a mixing device having a mixing chamber into which a rotor extends, the interior surface of said mixing chamber and the surface of the said rotor being provided with pins in staggered relation which serve to give the material a preliminary beating before it passes between the rotor and stator surfaces of the mill.

With these and other objects in view, this invention embraces broadly the concept of providing a mill having a mixing chamber and a rotor extending into the chamber, said mill being provided with means to feed the material in a small stream upon the center of the rotor surface. The mill is also provided with means by which the material entering the mill is subjected to a preliminary beating before it passes between the rotor and stator surfaces. In one form of the invention means mounted on the center of the rotor is provided which aids in the distribution of the material over the rotor surface after it has entered the mill.

The feeding principle is important because it enables the rotor surface to be covered with the incoming material without danger of overloading the mill, and the preliminary beating of the material eliminates the necessity of thoroughly mixing the materials before they are introduced to the mill and also eliminates the possibility of the ingredients separating before they reach the rotor and stator surfaces. These advantages will be subsequently described in more detail.

In the drawings:

Figure 1 is a view in longitudinal section of one form of the invention.

Figure 2 is a view taken along line 2—2 of Figure 1, looking in the direction of the arrows.

5 Figure 3 is a sectional view showing the rotor construction of another form of the invention.

Figure 4 is a sectional view showing the rotor construction of a third form of the invention.

For purposes of illustration three mill heads 10 have been shown in the drawings, all of which are capable of carrying out the principal objects of the invention. In the preferred form of the invention shown in Figures 1 and 2 of the drawings, the mill comprises a mill supporting structure, generally designated by the numeral 1, which is provided with a base 2, which rests on the end plate 3 of an electric motor, and carries a supporting structure 4.

The supporting structure 1 is provided with an inclined surface 5 positioned between a pair of side walls which form a chute 6 which converges at the foot of the inclined surface 5 to form the discharge spout 7. The front of the chute 6 is partially closed by a splash plate 8 which is held in position by knurled nuts 9 which engage studs 10 carried by the member 1. The inclined surface 5 is also provided with jackets 10' through which steam or cooling liquid may be introduced if desired.

20 30 The shaft 11 of the electric motor is coupled at 12 to a shaft 13 which drives a rotor member 14. The shaft 13 is journaled as indicated at 15 and 15' in a sleeve 16 which forms a part of the support structure 1 extending into the chute 6.

35 The upper portion of the support 1 defines an aperture 17 around the periphery of which is mounted a collar 18 which is held in place by cap screws 19. Adjusting bolts 19' which are carried by brackets 20 mounted on the member 1 afford means whereby the collar 18 may be adjusted centrally with respect to the rotor shaft 13. The upper portion of the collar 18 is exteriorly threaded as shown at 21 and is adapted to receive an interiorly threaded annulus 22 which can be rotated to raise or lower its position by means of handles 23.

40 45 A head 24 is detachably mounted within the collar 18 and extends into the aperture 17. The head 24 is provided with a steam or water jacket 25 which is connected by means not shown to a suitable supply of cooling or heating fluid and surrounds a central mixing chamber 26 of frusto-conical shape formed by walls 27.

55 55 The head 24 is provided with a flange 28 which

rests on the top of the annulus 22 and is secured to the collar 18 by studs 29 provided with wing nuts 30.

The upper portion of the head 24 is provided with a centrally located aperture 31 the periphery of which is threaded and adapted to engage the externally threaded extension 32 of a funnel or hopper 33. The aperture 31 may be of any suitable size but it is substantially smaller than the diameter of the frusto-conical shaped rotor 14, and positioned directly above the center of the rotor in order that the incoming material will be directed upon the center of the rotor.

The clearance between the rotor 14 and the walls 27 of the mixing chamber 26 is controlled by raising or lowering the head 24 by changing the position of the threaded supporting annulus 22. After the proper adjustment has been made, the wing nuts 30 are tightened to hold the head 24 in fixed position.

The rotor 14 extends into the mixing chamber 26 and its flat upper and sloping side surfaces are provided with interlacing disturbing elements such as pins or interrupting circular vanes 34 which extend in the direction of and approximately to the walls 27 when the head 24 is in normal operating position. These pins are of different heights and are arranged in four series.

The first two series are mounted on the flat upper surface of the rotor 14, the longest pin of each series being mounted adjacent the center of the rotor and the heights of the remaining pins becoming progressively less towards the periphery of the flat surface. The remaining two series are mounted on the sloping surface, the longest pin being mounted adjacent the intersection of this surface with the flat upper surface of the rotor and the lengths becoming progressively less as the lower periphery of the sloping surface is approached.

A propeller-like member 35 is rigidly mounted on the center of the rotor 14 between the longest pins of the first two series. This member 35 is provided with rigidly mounted vanes 36 which are curved in such a manner as to impel the incoming material towards the rotor surface.

The inner surface of the wall 27 is also provided with pins 37 which project into the mixing chamber 26 to a point adjacent the sloping surface of the rotor 14. These pins form two series which decrease progressively in length as they extend down the wall 27. They are also staggered in respect to the portion of the pins 34 mounted on the sloping surface of the rotor 14 to provide thorough mixing of materials being fed over the rotor.

In operation, the head 24 is adjusted in the manner previously described so as to provide the proper clearance between the interior surface of the mixing chamber 26 and the working surface of the rotor 14 and the mixture is then poured into the funnel 33 until a sufficient quantity has entered the mixing chamber 26 to completely cover the surface of the rotor. If desired, under some conditions the entire mixing chamber 26 may be filled with the rough mixture before the mill is started. However, under normal conditions only sufficient material is admitted to cover the rotor 14 before it is started.

During operation, because of the restrictive area of the aperture 31, all of the material entering the mixing chamber 26 comes in contact with the propeller 35 the vanes of which distribute the mixture evenly over the rotor surface. It is then subjected to a beating and mixing action by the pins 34 and 37. After a thorough beating

and mixing, the material passes between the working surfaces of the rotor 14 and the wall 27 and falls upon the inclined surface 5. After flowing down this surface it is discharged through the aperture 7.

In connection with the operation of this mill, it should be noted that the relatively small area of the aperture 31 in relation to the head of the rotor 14 permits only a restricted quantity of the material to be fed into the mill and directs all of this material upon the propeller 35 from which it can be evenly distributed over the rotor. The frusto-conical shape of both the rotor 14 and the mixing chamber 26 is also admirably suited for this type of mill and the pins 34 and 37 are strategically located so as to take full advantage of this construction and thereby give the mixture a thorough beating before it passes beyond the rotor 14.

In Figure 3 is shown a head 50 which may readily be substituted in the mill just described in place of the head 24. The head 50 is similar in construction to the head 24 and is provided with the previously described fluid chamber 25, flange 28, and central aperture 31 on which may be mounted the funnel 33 in the manner which has previously been described. The mixing chamber 51, however, of the head 50 is cylindrical in shape and is associated with a rotor 52 which is of hemispherical shape.

Mounted on the exterior surface of the rotor 52 are radially extending interlacing disturbing elements such as pins or interrupting circular vanes 53 which extend to a point adjacent the interior surface of the cylinder 51. These pins are arranged in two series, the longest pins of each series being offset slightly from the center of the rotor 52 and the pins of each series decreasing progressively in length as they extend down the slope of the rotor. Mounted on opposed surfaces of the cylinder 51 are a series of pins 54 which extend radially inward toward the center of the rotor 52. These pins are of equal lengths and extend to a point adjacent the surface of the rotor 52 and are staggered in relation to the pins 53.

In the construction just described it should be noted that the area of the aperture 31 is relatively small in comparison to the upper face of the rotor 52. However, due to the sharp slope of the surface of the rotor 52, this mill is capable of handling material of a given viscosity more rapidly than the frusto-conically shaped rotor 14 and the use of a propeller member 35 is therefore not necessary. The pins were positioned after a careful study of the shape of the mixing chamber 51 and the rotor 52 in order to obtain a maximum beating action.

In the modification shown in Figure 4, the head 60 is also provided with a fluid chamber 25, flange 28 and inlet aperture 31. The mixing chamber 61, however, is of conical shape and its interior wall is provided with interlacing disturbing elements such as pins or interrupting circular vanes 62 which are divided into two series and decrease progressively in size as they extend down the surface of the mixing chamber. These pins terminate adjacent the conical surface of a rotor 63 on the upper surface of which are mounted two series of pins 64. The longest pins of each series are mounted adjacent the center of the rotor 63 and the remaining pins of each series decrease progressively in height, the shortest pins being located adjacent the periphery of the rotor. The pins 62 and 64 are staggered.

In connection with this modification, it should

be noted that the aperture 31 is also of relatively small area as compared to the area of the upper surface of the rotor 63 and that the pins are positioned in such a manner as to give a maximum beating action when used in connection with a chamber and rotor of the type described. The conical-shaped rotor 63, due to the angle of its surface, is capable of handling material of a given viscosity more rapidly than is the rotor 14 but less rapidly than the rotor 52.

While for purposes of illustration the preferred structure which constitutes the invention has been shown and described, it is obvious that various changes in the details of construction can be made by those skilled in the art without departing from the spirit of the invention or exceeding the scope of the appended claims.

I claim:

1. An improvement in a mixing and emulsifying mill comprising a mixing chamber having walls, said mixing chamber being of frusto-conical shape, a rotor extending into said mixing chamber, said rotor being of frusto-conical shape and having a flat upper surface and sloping sides, an opening in the mixing chamber above the center portion of said rotor, a propeller rigidly mounted in the center of the rotor directly below the said opening, the vanes of said propeller being turned in a direction which enables it to distribute the material upon the rotor surface, two series of pins which progressively decrease in length mounted on the upper surface and extending down opposed sloping sides of the rotor, the longest pin of each series being positioned on opposite sides of the propeller adjacent the center of the rotor, and two series of pins mounted on the interior surface of the mixing chamber and extending towards the sloping surface of the rotor, the pins of each of said series decreasing progressively in length as they extend down the sloping interior of the mixing chamber, the last pin in each series being the shortest, and said pins being in staggered relationship in respect to the pins mounted on the sloping surface of the said rotor.

2. An improvement in a mixing and emulsifying mill comprising a mixing chamber having walls, said mixing chamber being of frusto-conical shape, a rotor extending into said mixing chamber, said rotor being of frusto-conical shape and having a flat upper surface and sloping sides, an opening in the mixing chamber above the center portion of said rotor, said opening being of relatively small size in respect to the rotor, a propeller rigidly mounted in the center of the rotor directly below the said opening, the vanes of said propeller being turned in a direction which enables it to distribute the material upon the rotor surface, two series of pins which progressively decrease in length mounted on the upper surface of the rotor and extending down opposed sides of the rotor, the longest pin of each series being positioned on opposite sides of the propeller adjacent the center of the rotor, and two

series of pins mounted on the interior surface of the mixing chamber and extending towards the sloping surface of the rotor, the pins of each of said series decreasing progressively in height as they extend down the sloping interior of the mixing chamber, the last pin in each series being the shortest, and said pins being in staggered relationship in respect to the pins mounted on the sloping surface of the said rotor.

3. An improvement in a mixing and emulsifying mill comprising a mixing chamber having walls, said mixing chamber being of frusto-conical shape, a rotor extending into said mixing chamber, said rotor being of frusto-conical shape and having a flat upper surface and sloping sides, the upper portion of the said mixing chamber defining an opening above the center portion of the said rotor, the area of said opening being of relatively small size compared to the area of the flat upper surface of the rotor, and said mixing chamber being adjustable in a vertical direction so that the distance between the upper surface of the rotor and the opening may be regulated, a propeller rigidly mounted on the center of the rotor directly below the said opening, the vanes of said propeller being turned in a direction which enables it to distribute the material upon the rotor surface, two series of pins which progressively decrease in length mounted on the upper surface of the rotor and extending down opposed sides of the rotor, the longest pin of each series being positioned on opposite sides of the propeller adjacent the center of the rotor, and two series of pins mounted on the interior wall of the mixing chamber and extending towards the sloping surface of the rotor, the pins of each of said series decreasing progressively in height as they extend down the sloping interior of the mixing chamber, the last pin in each series being the shortest, and said pins being in staggered relationship in respect to the pins mounted on the sloping surface of the said rotor.

4. An improvement in a mixing and emulsifying mill comprising a mixing chamber having walls, said mixing chamber being of frusto-conical shape, a rotor extending into said mixing chamber, said rotor being of frusto-conical shape and having a flat upper surface and sloping sides, an opening in the mixing chamber above the center portion of said rotor, two series of pins which progressively decrease in length mounted on the upper surface and extending down opposed sloping sides of the rotor, the longest pin of each series being positioned on opposite sides of the center of the rotor, and two series of pins mounted on the interior surface of the mixing chamber and extending towards the sloping surface of the rotor, the pins of each of said series decreasing progressively in length as they extend down the sloping interior of the mixing chamber, the last pin in each series being the shortest, and said pins being in staggered relationship in respect to the pins mounted on the sloping surface of the said rotor.

WILLIAM A. McLEAN.
